US00D784412S

(12) **United States Design Patent** (10) **Patent No.:** **US D784,412 S**
(45) **Date of Patent:** **** Apr. 18, 2017**

(54) **ELECTRONIC DEVICE**

(71) Applicant: **Apple Inc.**, Cupertino, CA (US)

(72) Inventors: **Jody Akana**, San Francisco, CA (US); **Bartley K. Andre**, Palo Alto, CA (US); **Shota Aoyagi**, San Francisco, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Matthew Dean Rohrbach**, San Francisco, CA (US); **Peter Russell-Clarke**, San Francisco, CA (US); **Mikael Silvanto**, San Francisco, CA (US); **Christopher J. Stringer**, Woodside, CA (US); **Eugene Antony Whang**, San Francisco, CA (US); **Rico Zörkendorfer**, San Francisco, CA (US)

(73) Assignee: **Apple Inc.**, Cupertino, CA (US)

(**) Term: **15 Years**

(21) Appl. No.: **29/545,929**

(22) Filed: **Nov. 17, 2015**

Related U.S. Application Data

(63) Continuation of application No. 29/504,186, filed on Oct. 2, 2014, now Pat. No. Des. 746,869, which is a (Continued)

(57) **CLAIM**

The ornamental design for an electronic device, as shown and described.

DESCRIPTION

FIG. 1 is a bottom perspective view of an electronic device comprising a cover showing our new design;

FIG. 2 is a top perspective view thereof;

FIG. 3 is a first side view thereof;

FIG. 4 is a second side view thereof, rotated by 90° clockwise from the first side view;

FIG. 5 is a third side view thereof, rotated 180° clockwise from the first side view; and,

FIG. 6 is a fourth side view thereof, rotated 270° clockwise from the first side view.

The broken lines illustrate structure which forms no part of the claimed design.

1 Claim, 6 Drawing Sheets

Related U.S. Application Data

continuation of application No. 29/457,337, filed on Jun. 9, 2013, now Pat. No. Des. 717,341.

(58) Field of Classification Search

CPC G06F 1/00; G06F 1/16; H05K 7/00
